US00D824460S

(12) **United States Design Patent** (10) **Patent No.:** **US D824,460 S**
(45) **Date of Patent:** **** Jul. 31, 2018**

(54) **ROBOTIC MODULE**

(71) Applicant: **Shenzhen Bell Creative Science and Education Co., Ltd.**, Shenzhen (CN)

(72) Inventors: **Zuobing Wang**, Shenzhen (CN); **Sheng Zan**, Shenzhen (CN)

(73) Assignee: **Shenzhen Bell Creative Science and Education Co., Ltd.**, Shenzhen (CN)

(**) Term: **15 Years**

(21) Appl. No.: **29/583,545**

(22) Filed: **Nov. 7, 2016**

(51) LOC (11) Cl. **21-01**

(52) U.S. Cl.

USPC **D21/578**; D15/199

CLAIM

The ornamental design for a robotic module, as shown and described.

DESCRIPTION

FIG. 1 is a top front perspective view of a robotic module showing the claimed design, a bottom rear perspective view being the same;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
